Primary Examiner — Ian Simmons*Assistant Examiner* — Khawaja Anwar(74) *Attorney, Agent, or Firm* — Gina T. Constant, Esq.(57) **CLAIM**

The ornamental design for a collapsible portable solar refrigerator design, as shown and described.

DESCRIPTION

FIG. 1 is a front perspective view of the a collapsible portable solar refrigerator device, shown in a collapsible configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view thereof; shown in a collapsed portable configuration;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines shown in the drawings represent unclaimed portions of the collapsible portable solar refrigerator device and form no part of the claimed design.
